ROTARY ACTUATOR

William M. Owens and Wilfred Hunter, Hertfordshire, England, assignors, by mesne assignments, to Ledex, Inc., Dayton, Ohio, a corporation of Ohio
Filed Oct. 19, 1961, Ser. No. 146,190
5 Claims. (Cl. 317—192)

This invention relates to rotary actuators adapted to convert an axial thrust to rotary movement and more particularly to an improved rotary actuator construction of the type described and claimed in association with an electromagnetic actuator in United States Letters Patent, No. 2,496,880, issued to George H. Leland, granted Feb. 7, 1950; however, the invention is not necessarily so limited.

An object of the present invention is to provide an improved mechanism for converting axial movement into rotary movement.

The basic mechanism, in its original form shown in the aforesaid patent, No. 2,496,880, constitutes a rotary solenoid comprising a fixed assembly including a housing and an electromagnet and a movable assembly including an armature and an output shaft. The armature is movable toward the magnet upon energization of the magnet while the output shaft is connected with the armature for rotation when the armature is attracted by the magnet. A plate is secured to the shaft connected with the armature and arranged in opposed relation to a surface portion of the housing. The plate and the aforesaid surface portion are separated by rotatable elements, preferably balls. The plate or the housing surface, or both of them, are provided with arcuate, inclined recesses presenting cam surfaces arranged with relation to the balls such that the action of the cam surfaces on the balls will cause the plate and armature to rotate when the armature is attracted toward the magnet. Specifically, the plate is normally biased so that a ball element is located within the shallow end of its recess, or recesses, as the case may be. Upon attraction of the armature toward the magnet, the ball elements are forced to roll along their corresponding recesses toward the deeper ends thereof. After each energization of the coil, the shaft and plate are returned to their initial positions at the shallow ends of the recesses.

This particular rotary mechanism has found wide commercial success in its original form and with minor variations. Units commercially available are typically capable of a million or more repeated operations. After extended use, however, portions of the mechanism are subject to wear and the rotary actuator in time operates erratically. To confine the ball elements between the plate and the opposed housing surface, a flange is secured to the shaft adjacent another surface of the fixed assembly. We have found that one of the greatest sources of breakdown of actuators of this type is this flange. The flange becomes worn and may even be severed from the shaft since it repeatedly strikes the adjacent surface of the fixed assembly as the plate and shaft return to their initial positions.

A further object of this invention is to prolong the useful life of rotary actuators of the type described above.

Other objects and advantages reside in the construction of parts, the combination thereof, the method of manufacture and the mode of operation, as will become more apparent from the following description.

In the drawings:

FIGURE 1 is an end elevational view of a rotary solenoid unit embodying the improvement of the present invention.

FIGURE 2 is a sectional view taken substantially along the line 2—2 of FIGURE 1.

2

FIGURE 3 is an enlarged fragmentary sectional view taken substantially along the line 3—3 of FIGURE 1.

Referring to the drawings in detail, the rotary solenoid comprises a housing which is preferably cylindrical in form and which includes a ferromagnetic cup-shaped casing 10 closed by a back wall or closure 12 for the open end of the casing. A ferromagnetic element 14 is arranged concentric within the casing 10 and press fit therein. A cylindrical inwardly directed portion of the element 14 provides a core 16 for the solenoid. The back wall 12 may be secured to the element 14 by screws 15 provided with heads (not shown) engaged within wells or recesses in the elements 14. An annular solenoid coil 18 extends about the core 16 within the casing 10, the coil being separated from the core and the casing by a suitable insulating member 20. The coil 18 and core 16 comprise a conventional electromagnet which may be electrically energized through suitable leads (not shown). The casing 10, the electromagnet and the back wall 12 remain in a fixed position throughout normal operation of the actuator. Hence, these elements are collectively termed a "fixed assembly" herein.

The central portion of the back wall 12 is apertured, the edges of the aperture being bent so as to form a rearwardly projecting annular spring housing 22 which encircles a coil return or reset spring 24, the purpose of which will be described later. An output shaft 26 is journaled for rotation in an aperture extending axially through the center of the core 16, concentric with the sides of the cup-shaped casing 10 and the spring housing 22. A cylindrical armature 30 is fixedly mounted upon the front end of the shaft 26. For this purpose, the armature 30 is provided with a central bore or axial aperture 32 while the forward portion of the shaft 26 is splined or knurled as indicated at 34 and press fit within the bore 32. The armature 30 and shaft 26 are permitted to slide axially relative to the fixed assembly. Therefore, the smaller diameter of the coil 18 is larger than the diameter of the armature 30 so that the armature 30 may move axially therein. Limitations upon the axial movement of the armature 30 and the shaft 26 will be discussed below.

It is evident that the magnetic field created upon energization of the coil 18 will draw the armature 30 axially into the casing 10. This axial motion is converted to a rotary motion to be impressed upon the armature 30 and the shaft 26 by the following means. Integral with the cup-shaped casing 10 and forming an apertured base or end portion thereof is an annular inwardly directed flange or surface portion 36. The surface portion 36 may be termed a fixed plate. The aperture within this plate has a diameter slightly greater than that of the armature 30, so as not to restrict its axial motion. The casing 10, including its flange portion 36, is ferromagnetic to provide a flux path for the magnetic field created upon energization of the coil 18. For best performance, the air gap between the plate or flange portion 36 and the armature 30 is as small as possible.

A movable disc or plate 38 is rigidly attached to the armature 30 for axial and rotary movement therewith in spaced relation to the outer surface of the flange portion or fixed plate. The opposing surfaces of the disc 38 and the flange portion 36 are each provided with three equally spaced arcuate inclined recesses 40 and 42, respectively. The disc or plate 38 is oriented initially with respect to the flange portion 36 such that the ends of the recesses 40 are substantially aligned with the ends of the recesses 42 of the flange portion 36. As shown in FIGURE 3, the bases of the recesses 40 and 42 are oppositely inclined. Disposed between each pair of opposing recesses 40 and 42, and in contact therewith, is a rotatable element, shown in FIGURES 2 and 3 as a ball bearing 44.

The spring 24, which is attached at one end to the spring housing 22 and at its other end to the shaft 26, biases the shaft 26 and plate 38 into a position wherein the ball bearings 44 normally occupy the extreme shallow ends of the recesses 40 and 42. To prevent the ball elements from dropping out of the aligned recesses 40 and 42, a flange is formed on or secured to the shaft 26 adjacent the rearward surface of the ferromagnetic element 14. The flange may conveniently be provided by a snap ring 46 seated within an annular groove in the shaft 26. The snap ring 46 is sufficiently spaced from the plate 38 to permit the ball elements 44 to occupy the shallow ends of the recesses 40, 42. On the other hand, the plate 38 and the snap ring 46 are sufficiently close that the plate 38 cannot move away from the flange portion 36 by an amount sufficient to permit the ball elements 44 to fall out of the opposed recesses 40, 42. Therefore, the ball elements 44 always remain confined between the plates 36 and 38.

In operation, electrical energization of the coil 18 creates a magnetic field drawing the armature 30 into the coil. The plate 38, accordingly, is driven inwardly toward the flange portion 36 of the cup-shaped casing 10. The inclined recesses 40 and 42 cooperate with the ball bearings 44 to permit axial motion of the plate 38 only if the plate 38 also rotates, allowing the ball bearings 44 to roll along the cam surfaces formed at the bases of the recesses 40, 42. That is, relative movement of the recesses 40 and 42 toward the ball elements 44 causes the plate 38 to rotate. The result is that the axial motion of the armature 30 is converted to rotary motion of the plate 38. For convenience, the shaft 26, armature 30 and plate 38 may be termed a "movable assembly." Since the movable assembly is driven upon energization of the coil, the resulting operation may be termed a "power stroke." FIGURE 3 shows the relative positions of a recess 40, a recess 42 and a ball element 44 at the end of a power stroke. Note that the ball element 44 in FIGURE 3 is cupped between the deep ends of the opposed recesses 40 and 42.

During the power stroke, the spring 24 is placed under increased tension. When the coil 18 is deenergized, the spring 24 returns or restores the movable assembly to its initial angular position, thus resetting the rotary mechanism. This return movement of the movable assembly may be termed the "return stroke." After completion of the return stroke, the movable assembly remains biased in its initial position by the spring 24 until the electromagnet is again energized.

The apparatus described above produces an angular displacement of the shaft 26 each time the coil 18 is energized, the displacement being counterclockwise, as viewed in FIGURE 1, for the particular structure shown in the drawings. The direction of rotation during the power stroke may be reversed by inverting the inclination of the recesses 40 and 42. It is to be noted that, in this particular embodiment, the shaft 26 is so attached to the armature 30 that it is both rotated and driven axially upon each energization of the coil 18. Similarly, during the return stroke, the shaft 26 is rotated in the opposite direction by the spring 24. The rotary mechanism converts the rotary movement imparted to the shaft 26 by the spring 24 into an axial movement of the movable assembly outwardly so that the armature 30 moves away from the core 16, that is, to the left as viewed in FIGURE 2.

At the end of the return stroke, the ball elements, which are rolling upwardly along the cam surfaces formed at the bases of the recesses 40, 42 strike the edges of the extreme shallow ends of the recesses. More precisely, of course, the extreme shallow end edge of each recess 40 strikes its associated ball element while the edge of the extreme shallow end of each recess 42 is struck by its associated ball element 44. In prior devices, the snap ring on the shaft struck the rearward face of the element

14 at substantially the same time as the ball elements reached the shallow ends of the recesses. Thus, the snap ring and the shallow ends of the recesses had to absorb much of the momentum of the movable assembly. The impact of the movable assembly against the fixed assembly caused considerable wear of both the shallow ends of the recesses and the snap ring. In time, the relatively small snap ring was severed from the shaft. When this occurred, the ball elements were no longer confined between the movable plate and the housing. The actuator thus became useless. This problem can be partially remedied by using a large flange on the shaft. However, the flange must be so massive that it may interfere with the normal construction and operation of the actuator.

In accordance with this invention, the useful life of the actuator may be prolonged without the use of an unduly large flange. Briefly stated, with this invention the impact of the snap ring 46 against the rear face of the element 14 is lessened by the provision of means to reduce gradually the momentum of the movable assembly at the end of the return stroke. In the specific embodiment disclosed in the drawing, this means comprises a yieldable, elastomeric washer 50 that encircles the shaft 26 and separates the snap ring 46 from the base of the ferromagnetic element 14. When the movable assembly completes its return stroke, the snap ring 46 engages a metal spacer or washer 52 interposed between the snap ring and the elastomeric washer 50, gradually placing the elastomeric member 50 under compression. Thus, the members 50, 52 cooperate with the flange 46 to stop the reset movement of the movable assembly. The purpose of the metal washer 52, which is the same size as the elastomeric member 50, is to obviate the deterioration of the elastomeric member 50 that would otherwise result should the snap ring 46 be permitted to rotatably engage the outer surface thereof. To reduce the axial length of the assembly, the central portion of the rear face of the ferromagnetic element 14 may be counterbored to provide a pocket for the elastomeric member 50. The mechanism is so designed that the snap ring 46 engages the washer 52 at substantially the same instant the ball elements 44 reach the shallow ends of their recesses. Accordingly, the ball elements 44 remain confined between these shallow ends.

It will be apparent that the interposition of the elastomeric member 50 between the snap ring 46 and the base of the ferromagnetic element 14 serves to provide a shock absorber or damper for the return movement of the movable assembly of the rotary actuator, gradually reducing much of its momentum. The resultant lessening of impact of the snap ring 46 with the rear face of the element 14 greatly increases the number of operations the actuator may undergo before the snap ring becomes fatigued and breaks down. As a result, the useful life of rotary actuators of this type has been extended in some cases by several million operations. Thus, although the change from the known prior art devices is only of a simple nature, the increase in the useful life of the actuator is quite dramatic.

Another advantage gained with this construction is the reduction in impact of the ball elements 44 with the shallow end edges of the recesses 40, 42. As the elastomeric member 50 compresses or yields at the end of the return stroke, the entire movable assembly is permitted to overtravel beyond its normal starting or deenergized position. The ball elements 44 accordingly may cam slightly outwardly along the shallow end edges of the recesses, or to the left as viewed in FIGURE 2, while the movable assembly is losing momentum. Thus, the sharp impact of the ball elements against the shallow ends of the recesses is reduced. This serves to prolong the life of the ball elements and to reduce the wear on the recesses.

Although the presently preferred embodiment of the device has been described, it will be understood that within the purview of this invention various changes may be

made in the form, details, proportion and arrangement of parts, the combination thereof and mode of operation, which generally stated consist in a device capable of carrying out the objects set forth, as disclosed and defined in the appended claims.

Having thus described our invention, we claim:

1. In a rotary actuator: a fixed assembly having spaced first and second surface portions and an aperture communicating between said surface portions; a shaft journaled for axial and rotary movement within said aperture and projecting beyond both of said surface portions; a plate connected to said shaft adjacent said first surface portion, one of said plate and said first surface portion having an arcuate inclined recess therein; a rotatable element in said recess interposed between and in contact with said plate and said first surface portion; a flange secured to said shaft adjacent said second surface portion, said flange and said plate being sufficiently spaced to permit said rotatable elements to engage the shallow ends of said recesses but sufficiently close to confine the rotatable elements between said plate and said first surface; drive means inducing relative axial movement between said plate and said first surface portion whereupon said shaft undergoes both rotary and axial movement causing said flange to move away from said second surface portion; means to reset said shaft, plate and rotatable element after each operation of said drive means whereupon said flange moves toward said second surface portion;

and yieldable means having a greater yielding capacity than that present in said fixed assembly at the second surface portion thereof interposed between said second surface portion and said flange, said flange striking said yieldable means at the end of the reset movement of said shaft, said yieldable means and said flange cooperating to stop the reset movement of said shaft.

2. The structure of claim 1 wherein said drive means includes an electromagnet forming a portion of said fixed assembly and an armature secured to said shaft for movement therewith, said armature being attracted toward said electromagnet upon each energization thereof.

3. The structure of claim 1 wherein said yieldable means includes an elastomeric washer encircling said shaft.

15 4. The structure of claim 3 wherein said yieldable means further includes a metal washer encircling said shaft and interposed between said elastomeric washer and said flange.

5. The structure of claim 3 wherein said second surface 20 is the rear surface of a core element for the electromagnet, said surface being counterbored to provide a pocket for said elastomeric washer.
